[57] CLAIM

The ornamental design for a splatter shield accessory for hand-mixers, as shown and described.

DESCRIPTION

FIG. 1 is a front elevational view of the splatter shield accessory for hand-mixers showing my new design;
FIG. 2 is a rear elevational view thereof;
FIG. 3 is a top plan view thereof; and,
FIG. 4 is a bottom plan view thereof.

The broken line showing of a mixer and a bowl in FIG. 1 is for illustrative purposes only and forms no part of the claimed design.
